Primary Examiner — Katrina A Betton(74) *Attorney, Agent, or Firm* — Knobbe, Martens, Olson & Bear LLP(57) **CLAIM**

The ornamental design for a truck bed rack support, as shown and described.

DESCRIPTION

FIG. 1 is a front perspective view of a truck bed rack support, which embodies our design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.
